DESIGN FOR A DUMPING VEHICLE

Emil L. Tranaas, Milwaukee, Wis., assignor to
Koehring Company, Milwaukee, Wis., a corpora-
tion

Application August 24, 1936, Serial No. 64,557

Term of patent 14 years

To all whom it may concern:

Be it known that I, Emil L. Tranaas, a citizen
of the United States, residing at Milwaukee, in
the county of Milwaukee and State of Wisconsin,
have invented a new, original, and ornamental
Design for a Dumping Vehicle, of which the fol-
lowing is a specification, reference being had to
the accompanying drawing, forming a part there-
of, in which:—

Fig. 1 is a perspective view showing a side and

one end of the dumping vehicle of my new design,
and

Fig. 2 is a perspective view taken from the
same side but showing the end opposite that illus-
trated in Fig. 1.

I claim:—

The ornamental design for a dumping vehicle
as shown.

EMIL L. TRANAAS.
